UNITED STATES PATENT OFFICE.

ROBERT WILLIARD PAIN, OF NEW YORK, N. Y., ASSIGNOR TO THE AEOLIAN COMPANY, OF CONNECTICUT.

PNEUMATIC PIANO-PLAYING DEVICE.

SPECIFICATION forming part of Letters Patent No. 674,426, dated May 21, 1901.

Application filed September 11, 1900. Serial No. 29,710. (No model.)

To all whom it may concern.

Be it known that I, ROBERT WILLIARD PAIN, a citizen of the United States, and a resident of New York, in the county of New York 5 and State of New York, have invented certain new and useful Improvements in Pneumatic Piano-Playing Devices, of which the following is a specification.

My invention relates generally to pneumatic piano-playing devices, and more particularly to the class of devices in which the primary valve-action is operated by impulses of air admitted by the passage of a perforated sheet of flexible material over a tracker-board.

One object of my invention is to produce a more compact and efficient device characterized by easier access to the operating parts, greater adjustability and adaptability, and a 20 reduction in the cost of production. Other objects will appear farther on in the specification.

The invention consists in the combination of co-operative elements hereinafter described; and it also pertains to a great extent to the arrangement of these elements.

In the accompanying drawings I have shown a device embodying my invention; but changes and variations in details of construction 30 may of course be made all within the scope of the claims.

In the said drawings, Figure 1 is a front view of a device embodying my invention shown partly in section. Fig. 2 is a transverse sectional view of same. Fig. 3 is an enlarged detail view of the means for adjusting the upper casing. Fig. 4 is an enlarged view in section of the upper portion of Fig. 2, taken on the line α α of Fig. 5. Fig. 5 is a plan view of Fig. 4 with the wall 39^a broken away. Fig. 6 is an end view showing the relative arrangement of the pneumatics.

Similar characters of reference indicate corresponding parts in the different views.

I shall describe a pneumatic piano-playing device embodying my invention and afterward point out the novel features in the claims.

The operating parts are inclosed in a suitable casing made in two parts—a lower stationary casing 1 and an upper adjustable cas-

ing 2. The lower stationary casing contains the pump or suction device, with its receiver, and also the means for operating same—viz., the pedals—together with such other means as are necessary for them to perform their proper function. The upper adjustable casing, on the other hand, carries the action of the mechanism—viz., the finger-pieces, pneumatics, tracker-board, music-roll, winding-up roll, wind-motor, pressure-regulating bellows, expression, and other regulating mechanism, together with suitable means of communication for the passage of the wind, connecting the different parts with each other. The upper casing fits within the lower casing and is adapted to be adjusted vertically with relation to the same in the following manner: The lower casing is formed with vertical guideways 3—two at each end—and is further provided at one of said ends with a horizontal and transversely-extending piece 4, resting on top of the inner wall of the guideways and attached to the same by suitable means. The upper casing is correspondingly provided with four vertical guides 5, adapted to slide in the guideways of the lower casing, and two of these guides 5 are connected by means of the cross-piece 6, placed directly above the cross-piece 4 of the lower casing. A vertical screw 7 is secured firmly to the cross-piece 6 and passes through a screw-cut hole in the cross-piece 4 and has mounted on it the interiorly-screw-cut pinion 8, which is held stationary against the stationary cross-piece 4 by suitable means, such as the cup-shaped device 9, shown in the drawings. With this pinion 8 meshes the worm 10, also mounted on the stationary cross-piece and provided at one end with a nut-face 11, which extends partially through the casing, access to the same being had through the aperture 12 by means of a removable key or wrench adapted to be inserted through the said aperture and to engage with the nut-face 11. If it is now desired to use at different times the playing device in connection with different pianos having different heights, the upper or playing portion may be adjusted to the required height by manipulating the worm 10 in the manner described, thereby turning the pinion 8, and the latter being stationary and in-

riorly screw-cut and mounted on the screw 7 will impart its motion to the said screw and cause it to travel in a vertical direction either up or down, according to the direction of the motion imparted, and to carry the upper or adjustable casing with it.

The suction device and adjacent elements will now be described. In the lower casing is attached the middle board 13, carrying, as usual, the receiver 14 and the two bellows forming the pump 15. These devices are provided with suitable valves, as at 16 and 16^a, and may be constructed in any manner best suited for the purpose. These bellows 15 are operated by means of two pedals 17, pivoted with one end to the inside of the vertical swinging door 18, as at 18^b, the said door being hinged at its lower end at 18^a in the casing, and carry at their other end a wire joint 19, to each of which is fastened the tape 20, passing over the pulley 21 and attached by means of the button 22 one to each of the bellows 15. By this means the pedals 17 are folded up when the door 18 is closed by sliding up against the wire guides 23 on the bellows 15, this movement being permitted by the wire joint 19 and the pivot 18^b on the door 18, while when the said door is opened the pedals drop into operative position, as shown by the dotted lines in Fig. 2. The sliding movement on the wire guides 23 is facilitated by forming the ends of the pedals 17 adjacent to same with a rounded portion 17^a. The pulleys 21 are pivoted on the pins 21^a, carried by the side pieces 21^b, which in their turn are fastened on the longitudinal board 21^c, attached by some suitable means, as the clefs 21^d, on the middle board 13. By this construction of the pedals a much more serviceable and convenient pumping device is produced, easier to gain access to, and more pleasing in appearance.

The upper part of the receiver connects, through the passage 24, with the bellows-throat 25, extending longitudinally across the mechanism, and this may be considered the termination of the elements carried by the lower casing. On account of the adjustability of the upper casing within the lower casing it becomes necessary, however, to interpose a compensating device between the upper and the lower casing which will adapt itself to the motion of the upper casing, so as to maintain the requisite communication between the operating parts and the suction device, and to this end the two flexible wind-trunks 26 and 27, one at each end of the casing, are provided by placing the longitudinal lower board 28 on top of the bellows-throat 25 and by securing the longitudinal upper board 29 to the upper casing, the wind-trunks being fastened between these. By this arrangement a flexible connection is established, so that the parts carried by the upper casing are in constant and unimpaired communication with the parts carried by the lower casing.

The parts carried by the upper casing will

now be described. 30 indicates the tracker-board, constructed in the usual manner, communicating by means of the alternating and flexible connections 31 and 31^a with two series of vertical passages 32 and 32^a, located opposite to each other on either side of the tracker-board in the outer side walls of the exhaust-chambers 33 and 33^a, extending longitudinally for almost the entire length of the casing. The vertical passages 32 and 32^a communicate at their lower ends, respectively, with the horizontal passages 34 and 34^a, which terminate in the apertures 35 and 35^a, piercing the wall into the exhaust-chambers, but covered with the flexible diaphragms 36 and 36^a. On the upper side of each of these diaphragms rest the lower ends of the puppet-valves 37 and 37^a, working in the horizontal passages 38 and 38^a between the walls 39 and 39^a and 40 and 40^a. The walls 39 and 39^a have each an aperture 41 and 41^a, connecting the passages 38 and 38^a with the atmosphere, and the walls 40 and 40^a have each an aperture 42 and 42^a, connecting the passages 38 and 38^a with the exhaust-chambers 33 and 33^a. Between the two inner side walls 43 and 43^a of the exhaust-chambers are located the pneumatics 44 and 44^a. To economize space, the pneumatics 44^a are carried by a block of wood 44^b, suspending them at a point somewhat lower than the point at which the pneumatics 44 are suspended. Only three pneumatics have been shown in the drawings; but it will of course be understood that they extend the entire distance of the exhaust-chambers, one pneumatic being provided for each separate tone. The pneumatics 44^a communicate by means of the passages 45 with the passages 38^a, and the pneumatics 44 communicate by means of the passages 45^a with the passages 38.

From the foregoing it will appear that when impulses of air are admitted through the tracker-board in a well-known manner through one of the flexible connections 31^a to the vertical passage 32^a and the passage 34^a the diaphragm 36^a will be inflated and lift the puppet-valve 37^a, and the latter, being formed with two buttons 37^b and 37^c, one of which is adapted when the valve is in its normal position to shut off communication between the exhaust-chamber 33^a and the passage 38^a, will shut off communication between the exhaust-chamber 33^a and the atmosphere and open the aperture 42^a, thus bringing the pneumatic 44 into communication with the exhaust-chamber 33^a, and thus exhaust the air contained in said pneumatic, causing it to collapse and to operate one of a plurality of finger-pieces 46. When the paper passing over the tracker-board shuts off the admission of air, the diaphragm collapses, and the puppet-valve with it, thus bringing the pneumatic into free communication with the atmosphere and causing it to expand again. The air which has been utilized in inflating the diaphragm passes slowly through the small aperture 47 into the exhaust-chamber. The

puppet-valves are supported in a well-known manner by suitable guides 47^a, while the finger-pieces 46 have one of their ends attached to a wire or screw 46^a, attached to the pneumatics, and are pivoted at their central portion in a series of slots 46^b, formed in the casing.

In the exhaust-chambers 33 and 33^a is maintained an approximate vacuum, the said chambers being connected to the suction device described above in the following manner: From each of the exhaust-chambers extends a pipe 48, passing down and connecting with the transverse channel 49, which communicates with the gate-box 50 through the aperture 50^a. The gate-box communicates through the passage 29^a in the upper board 29 with the pressure-regulating bellows 51, which bellows has a passage 51^a connecting with the flexible wind-trunk 26. The construction and function of the pressure-regulating bellows are well known in the art, the wind being caused to pass through the same by a suitable valve mechanism when soft playing is desired, while when the full force of the bellows is desired the wind is passed directly from the gate-box 50 through the aperture 50^b and the aperture 50^c to the flexible wind-trunk 26. In like manner the motor for operating the winding-up roll and the music-roll (shown diagrammatically at 52) is connected, by means of the pipe 52^a, to the gate-box 53^b and the pressure-regulating bellows 53^c, communicating with the flexible wind-trunk 27.

From the above it will be seen that the wind travels from the pneumatics to the exhaust-chambers through the pipe 48 and the transverse channel 49 to the gate-box 50 and from thence either direct or through the pressure-regulating bellows 51 to the flexible wind-trunk 26. At this point it passes into the elements located in the stationary casing through the bellows-throat 25 into the receiver 14, from whence it is exhausted by means of the pump 15.

The wind from the motor passes in the manner described above through the pipe 52 to the gate-box 53^b, bellows 53^c, and flexible wind-trunk 27, and from thence into the bellows-throat, where it is exhausted, together with the wind from the pneumatics.

The wind passing through the tracker-board after being utilized to inflate the diaphragms 36 and 36^a passes through the apertures 47 into the exhaust-chambers and from there is exhausted with the wind from the pneumatics in the manner described above.

Having thus described my invention, what I claim is—

1. In a device of the character set forth, the combination of a lower, stationary casing, an upper, movable casing, a suction device, a receiver, a middle board interposed between the suction device and the receiver, a bellows-throat extending longitudinally over the top of the middle board, all located in the stationary casing and communicating with each

other, a plurality of pneumatics, a wind-motor for operating the same and a pressure-regulating device, all located in the movable casing and communicating with each other, and a flexible wind-trunk interposed between the elements contained in the upper casing and the elements contained in the lower casing, adapted to compensate for the movement of the movable casing, substantially as described.

2. In a device of the character set forth, the combination of a lower, stationary casing, an upper, movable casing, a plurality of pneumatics having means adapted to coact with a tone-producing device and a wind-motor both located in the movable casing, a suction device located in the stationary casing, a separate means of communication from the pneumatics and the wind-motor respectively to the suction device having each interposed a flexible connection adapted to compensate for the movement of the movable casing, and a longitudinally-extending bellows-throat forming a common intermediate means connecting the separate means of communication with the suction device, substantially as described.

3. In a device of the character set forth, the combination of a lower stationary casing, with an upper, movable casing, a plurality of pneumatics having means adapted to coact with a tone-producing device and a wind-motor, both located in the movable casing, a suction device and a longitudinally-extending bellows-throat located in the stationary casing, a rigid support extending longitudinally in the casing and attached to the bellows-throat, a second rigid support also extending longitudinally and attached to the movable casing, two flexible wind-trunks interposed between the rigid supports both discharging into the bellows-throat, a means of communication from the pneumatics to one of said wind-trunks, and a separate means of communication from the wind-motor to the other of said wind-trunks, substantially as described.

4. In a device of the character set forth, the combination of a lower stationary casing, an upper movable casing, two longitudinally-extending exhaust-chambers, a plurality of pneumatics alternately arranged with regard to said exhaust-chambers and operatively connected with same, a transverse channel, means of communication between the transverse channel and the exhaust-chambers, a gate-box communicating with the transverse channel, all located in the movable casing, a suction device located in the stationary casing, a flexible connection between the suction device and the gate-box adapted to compensate for the movement of the movable casing, a pressure-regulating device, and means for connecting at will the gate-box with the flexible connection direct or through the pressure-regulating device, substantially as described.

5. In a device of the character set forth, the combination of a lower, stationary casing, an

upper, movable casing, a plurality of pneumatics having means adapted to coact with a tone-producing device located in the movable casing, a suction device located in the stationary casing, two longitudinally-extending rigid supports one of which is stationary with the lower casing, while the other is carried by the movable casing, a flexible connection interposed between the two rigid supports communicating with the suction device and adapted to compensate for the movement of the movable casing, a gate-box and a pressure-regulating device both located on the upper side of the rigid support on the movable casing, means of communication between the pneumatics in the movable casing and the gate-box, a passage through the rigid support carried by the movable casing connecting the gate-box with the flexible connection, a second passage in said rigid support connecting the gate-box with the pressure-regulating device, and a passage from said pressure-regulating device through the rigid support to the flexible connection, substantially as described.

6. In a device of the character set forth, the combination of a lower stationary casing, an upper, movable casing, a plurality of pneumatics having means adapted to coact with a tone-producing device and a wind-motor, both located in the movable casing, a suction device located in the stationary casing, two horizontally-extending rigid supports, one of which is stationary with the lower casing while the other is carried by the movable casing, two separate flexible connections interposed between the two rigid supports both connecting with the suction device and adapted to compensate for the movement of the movable casing, two gate-boxes and two pressure-regulating devices all located on the upper side of the rigid support of the movable casing, one gate-box and one pressure-regulating device being located at each end, means of communication between the pneumatics in the movable casing and one of said gate-boxes, means of communication between the wind-motor and the other of said gate-boxes, a passage from each of said gate-boxes, through the rigid support carried by the movable casing, to its respective flexible connection, a second passage from each of said gate-boxes through the same rigid support to its respective pressure-regulating device, and a passage from each of said pressure-regulating de-

vices through the rigid support to the same flexible connection with which its respective gate-box communicates, substantially as described.

7. In a device of the character set forth, the combination with an exhaust-chamber of a tracker-board, a vertical passage formed in the side wall of the exhaust-chamber, a flexible connection between the tracker-board and the vertical passage, a horizontal passage formed in the lower wall of the exhaust-chamber and communicating with the vertical passage, an aperture from the horizontal passage to the exhaust-chamber, an inflatable diaphragm covering same, a puppet-valve resting with its lower end on said diaphragm and adapted to be lifted by it when impulses of air are admitted from the tracker-board, and a perforation from the vertical passage to the exhaust-chamber for the exhaust of the impulses of air utilized in inflating the diaphragm, substantially as described.

8. In a device of the character set forth, the combination of two longitudinally-extending exhaust-chambers, a transverse connection securing said exhaust-chambers together, two series of pneumatics alternately arranged and located between the exhaust-chambers underneath the transverse connection, two series of transverse passages alternately arranged to correspond with the two series of pneumatics located in the transverse connection, one series of the transverse passages connecting one series of the pneumatics with one of the exhaust-chambers, and the other series of transverse passages connecting the second series of pneumatics with the second exhaust-chamber, substantially as described.

9. In a device of the character set forth, the combination of a bellows, a vertical swinging door hinged in the casing of the device, a pedal pivoted with one end to the inside of the swinging door and moving with same, a wire joint carried by the other end of said pedal, a pulley, a tape passing over said pulley securing the bellows and the wire joint together, and two wire rails on the bellows for the pedal to slide upon to its closed position, when the door is closed, substantially as described.

Signed at New York, in the county of New York and State of New York.
